Primary Examiner — T. Chase Nelson*Assistant Examiner* — Eric L Goodman(74) *Attorney, Agent, or Firm* — Bateman IP Law Group(57) **CLAIM**

The ornamental design for an in-line occluder, as shown and described.

DESCRIPTION

FIG. 1 shows a right side view of an in-line occluder made in accordance with the design of the present invention, the left side view being a mirror image thereof;

FIG. 2 shows a top view of the in-line occluder of FIG. 1 made in accordance with the present invention, the bottom view being a mirror image thereof;

FIG. 3 shows a front end view of the in-line occluder of FIG. 1 made in accordance with the present invention;

FIG. 4 shows a rear end view of the in-line occluder of FIG. 1; and,

FIG. 5 shows a perspective view of the in-line occluder of FIG. 1.

The broken line showing is included for the purpose of illustrating portions of the article that form no part of the claimed design.
